UNITED STATES PATENT OFFICE.

EBENEZER A. W. JEFFERIES AND GEORGE H. ISLEY, OF WORCESTER, MASSACHUSETTS,
ASSIGNORS TO MORGAN CONSTRUCTION COMPANY, OF WORCESTER, MASSACHUSETTS,
A CORPORATION OF MASSACHUSETTS.

GAS-PRODUCER.

1,142,100.

Specification of Letters Patent. Patented June 8, 1915.

Application filed March 2, 1908. Serial No. 418,656.

To all whom it may concern:

Be it known that we, EBENEZER A. W. JEFFERIES and GEORGE H. ISLEY, citizens of the United States, residing at Worcester, in the county of Worcester and Commonwealth of Massachusetts, have invented a new and useful Improvement in Gas-Producers, of which the following is a specification accompanied by drawings, forming a part of 10 the same, in which—

Figure 1 represents a vertical central sectional view of a gas producer embodying our invention. Fig. 2 is a plan view of the supporting rolls upon which the rotating 15 portion of the gas producer is mounted.

Similar reference characters refer to similar parts in the different views.

Our invention relates to that class of gas producers designed for the production of 20 fuel gas for metallurgical or other purposes, comprising a gas producing chamber in which carbon monoxid is produced by the action of air and steam upon a mass of incandescent coal.

25 In the gas producer embodying our invention fresh coal is introduced at the top of the chamber and rests upon the mass of incandescent coal, in which combustion is maintained by a charge of air and steam admitted at the bottom of the chamber. The resulting ash is contained in a hopper below 30 the gas producing chamber and delivered through the open bottom of the hopper into an ash pan, from which the accumulated 35 ash is removed either by hand or by mechanical means.

In the accompanying drawings we have not shown mechanical means for either removing the ash from the ash pan or for 40 feeding the coal to the gas producing chamber, as these may be of any known and suitable type now in common use.

45 It is the object of our invention to increase the efficiency of gas producers of this class as it relates to the cost, character and quantity of the gas produced, by means of the construction and arrangement of parts as hereinafter described, the novel features being pointed out in the annexed claims.

50 Our improved gas producer, as illustrated in sectional view in Fig. 1, consists of a metallic stationary shell or casing 1 supported upon upright posts, one of which is shown

at 2. The lower edge 3 of the casing 1 extends into an ash pan 4 and below a water line 5 maintained in the ash pan, thereby producing a water seal for the lower edge of the casing 1. The casing 1 extends radially inward to form a horizontal shelf 6, upon which a brick wall 7 is supported, forming 60 a lining for the upper portion of the gas producing chamber. From the horizontal shelf 6 the casing 1 extends downward in the form of a depending wall to a horizontal plane, indicated by the line 8, at or near the 65 bottom of the hot zone in the gas producing chamber, and from the plane of the line 8 the shell 1 extends obliquely upward and outward to a horizontal plane slightly above the shelf 6, inclosing an annular water 70 chamber 9 substantially triangular in cross section.

From the outer edge of the water chamber 9 the casing 1 descends into the ash pan 4, with the lower portion gradually contracted 75 in diameter, making the lower end of the casing hopper shaped. The gas producing chamber 10 is inclosed at its upper section by the brick wall 7, and at its lower section by that portion of the metallic casing 1 80 forming the inner wall of the triangular water chamber 9.

The top of the chamber is covered by a plate 11 having suitable openings 12, 12, for the introduction of fuel and for the inspection of the interior of the producer. 85

Inclosed within the lower end of the casing 1 and partially inclosing the water chamber 9 is an ash hopper 13, which is hopper shaped, corresponding with the 90 lower section of the casing 1 and constructed with double walls 14, including a water space 15 open at the top and closed at the bottom. The ash hopper 13 rests at intervals upon legs 16 which are supported by 95 the ash pan 4.

Mounted upon the ash pan 4 is a cone 17, having at the top a series of annular slits 18 for the admission of air and steam to the gas producer chamber, in the manner common in 100 gas producers of this class. The outer wall of the ash pan 4 is preferably inclined forming a V-shaped annular space 19 between the outer wall of the pan and the cone 17, for the accumulation of ash from the 105 ash hopper 13.

The bottom of the ash pan comprises an annular rim 20 which is supported upon three conical rollers 21, mounted in suitable equidistant bearings in the same horizontal plane. One of the rollers 21 has its shaft extended at 22 and connected with a suitable driving mechanism consisting, in the present instance, of a worm gear 23 and a worm 24 upon a driving shaft 25, to which 10 rotary motion is imparted in any convenient manner. The use of three supporting rollers 21 enables the weight of the ash pan and the structures supported thereon to rest with uniform pressure upon the rollers, so that 15 the rotation of any one of them will cause a rotary motion to be imparted to the ash pan 4, cone 17, and the ash hopper 13.

The cover 11 is provided with upturned edges 26 forming a pan for the reception of 20 water, for the purpose of sealing the covers 27 of the openings 12. The water employed as a sealing medium for the cover 11 overflows through a pipe 28 into the ash pan 4. The water chamber 9 is supplied with water 25 from any convenient source and overflows through a pipe 29 into the water space 15 between the double walls of the ash hopper 13. The overflow from the water space 15 is caught by the annular ash pan 4, in 30 which a water line is maintained by means of an overflow pipe 30, in order to secure a permanent water seal for the lower edge of the producer shell or casing 1.

During the operation of our improved 35 gas producer coal is fed through the openings 12 in a comparatively thin layer over the fire, and steam or air is admitted through the annular slits 18 in the well known manner. The interior of the gas 40 producer may be roughly divided into three horizontal portions as follows; at the bottom, the portion below the line 8 which is arranged to contain the ash from the consumed fuel; immediately above the line 8, 45 the so called hot zone or region of the most active combustion with a layer of unignited fuel above it, and in the upper part of the producing chamber the accumulation of manufactured gas. The central horizontal 50 portion is designed in the construction of the producer to inclose practically all of the ignited and incandescent fuel, and in operation a slow rotative movement is imparted to the ash pan 4 and ash hopper 13. As the 55 contents of the ash hopper are slowly rotated, there will be a plane of cleavage between the moving contents of the ash hopper and the superimposed mass of fuel contained in the gas producer chamber proper, 60 and substantially on the plane of the line 8. This plane of cleavage is located above the apex of the cone 17 and near the bottom of that portion of the producer designed to 65 contain the ignited fuel. Agitation of the mass of coal between the stationary and ro-

tating portions prevents the caking of the incandescent coal and the formation of air passages or pipes.

By constructing the inner wall of that portion of the gas producing chamber subjected to the greatest heat of metal, which is water cooled by means of the annular chamber 9, we prevent the accretion of clinkers upon the inner surface of the gas producing chamber, and with a lining wall 75 of brick we obviate all undue abstraction of heat from the manufactured gas, which accumulates in the upper portion of the chamber and is withdrawn therefrom through the opening 31. The ash hopper 13 is constructed of metal water cooled by the water opening in the space 15, which prevents the accretion of clinkers and facilitates the downward movement of the ash and clinkers into the ash pan 4.

We claim,

1. A gas producer having a stationary casing and an ash pan, with said casing extending into said ash pan to form a seal for the casing, an ash hopper inclosed within the lower part of said casing, and means for rotating said hopper.

2. A gas producer having a stationary casing and an ash pan, with said casing extending into said ash pan to provide a seal for said casing, an ash hopper supported upon said ash pan and inclosed in said casing, and means for rotating said pan and hopper.

3. A gas producer having a stationary casing, a rotatable ash hopper inclosed within the lower part of said casing, and a water seal between the lower edge of said ash hopper and the lower edge of said casing.

4. A gas producer having a casing divided horizontally with the upper portion stationary and the lower portion revolute, said upper portion having a downward extension over said lower portion and provided with a water seal at its lower edge.

5. A gas producer comprising a casing divided horizontally, with the upper portion stationary and the lower portion revolute, and a downward extension from said upper stationary portion inclosing said lower revolute portion.

6. A gas producer comprising a stationary metallic casing, a revolute ash pan below said casing, means for rotating said ash pan, a central cone in said pan forming with the side of the pan an annular space for ash, and a hopper-shaped ash receptacle supported by said pan and inclosed within the lower portion of said stationary casing.

7. A gas producer comprising a stationary casing forming a gas producing chamber arranged to contain the fuel in the process of combustion, a rotatable ash pan inclosing the lower end of said casing, and an ash hop-

per supported on said ash pan and extending into said casing.

8. A gas producer comprising a casing divided horizontally, with the upper portion stationary and the lower portion revoluble, an ash pan below said lower portion, and a downward extension from said upper stationary portion inclosing said lower portion and extending into said ash pan.
- 10 9. A gas producer comprising a casing divided horizontally, with the upper portion stationary and the lower portion revoluble, with the lower end of said upper portion extending downwardly inside and below the 15 top of said lower portion, and means for maintaining a body of water in contact with said downwardly extending end.

10. A gas producer comprising a stationary casing, with part of said casing forming the inner wall of a portion of the gas producing chamber, means for maintaining a body of water in contact with said inner wall, an ash pan inclosing the lower end of said casing, and a revoluble hopper inclosed 25 within said casing and forming the lower portion of said chamber below said inner wall.

11. A gas producer comprising a casing divided horizontally, with the upper section stationary and the lower section revoluble, with the upper portion of the revoluble section inclosing a depending wall of the stationary section, with an annular water chamber surrounding said depending wall.

35 12. A gas producer comprising a casing divided horizontally into two sections, with the upper section stationary and the lower section revoluble, said upper section having a depending wall extending within the upper edge of said revoluble section.

13. In a gas producer a casing inclosing a gas producing chamber, a rotatable ash pan below said chamber, a central cone in said ash pan having means for the admission of air to said chamber, said cone having inclined sides extending to the bottom of said ash pan, with the outer wall of said ash pan also inclined and arranged to intersect the inclined sides of said cone, thereby forming an annular space having a closed V-shaped bottom for the reception of ashes, and means for rotating the ash pan.

45 14. In a gas producer, a revoluble ash pan, an ash hopper supported by the pan, means for rotating the ash pan and hopper, a casing extending above the hopper to inclose a gas producing chamber, and a water seal between the pan and the casing.

50 15. In a gas producer, a revoluble ash pan, an ash hopper supported by the pan and extending into the pan to form a water seal, means for rotating the ash pan and hopper, a casing extending above the hopper to inclose a gas producing chamber, and a water seal between the pan and the casing.

55 16. In a gas producer, a revoluble ash pan, an ash hopper supported by the pan, there being an opening between the hopper and pan to permit removal of ash, means for rotating the ash pan and hopper, a casing surrounding the hopper and extending above the same to inclose a gas producing chamber, and a water seal between the pan and the casing.

60 Dated this 28th day of February 1908.
